Primary Examiner — Omeed Agilee(74) *Attorney, Agent, or Firm* — Michael J. Feigin, Esq.; Feigin and Fridman LLC(57) **CLAIM**

The ornamental design for an in vitro diagnostic device (IVD), as shown and described.

DESCRIPTION

FIG. 1 is a perspective view of an in vitro diagnostic device (IVD).

FIG. 2 is a second perspective view thereof with a closed lid

.

FIG. 3 is a perspective view thereof with an open lid.

FIG. 4 is a front view thereof with an open lid.

FIG. 5 is a rear view thereof with an open lid.

FIG. 6 is a top view thereof with an open lid.

FIG. 7 is a bottom plan view thereof with an open lid.

FIG. 8 is an enlarged right side view thereof; and,

FIG. 9 is an enlarged left side view thereof.

The broken lines depict portions of the in vitro diagnostic device (IVD) that form no part of the claimed design.
